UNITED STATES PATENT OFFICE.

WILLIAM A. C. MATTHIE, OF MONTREAL, QUEBEC, CANADA.

PIANO-STOOL.

SPECIFICATION forming part of Letters Patent No. 316,281, dated April 21, 1885.

Application filed December 5, 1884. (No model.) Patented in Canada, November 29, 1884, No. 20,670.

To all whom it may concern:

Be it known that I, WILLIAM AUGUSTUS CHAPMAN MATTHIE, of the city of Montreal, in the county of Hochelaga, in the Province 5 of Quebec, Canada, gentleman, have invented a certain new and useful Device for Elevating and Securing in any Desired Position Piano-Stools and other Analogous Extensible Articles; and I do hereby declare that the following is a full, clear, and exact description of the same.

The invention relates to piano-stools or other analogous articles; and it consists in the peculiar combinations and the construction 15 and arrangement of parts, hereinafter more fully described and claimed.

Figure 1 is a sectional elevation of a music-stool provided with my improved device. Fig. 2 is an enlarged detail, partially in section, showing the locking portion of the device.

As will be understood on reference to the drawings, the device which I shall now describe is not only applicable to piano-stools, 25 as illustrated, but is also of equal value in extensible chairs, foot-rests, tables, reading-desks, drawing-tables, photographers' head-rests, reading and music stands, and, in fact, in any article arranged to be extensible; but 30 for the purpose of this description it will be sufficient to show its application to a single article, and I have therefore chosen a music-stool for that purpose.

A represents the seat of the music-stool 35 connected to a spindle, B. This spindle fits in the usual way into an annular chamber formed in the stand C. At the bottom of the chamber I place a spiral spring, D, of sufficient power and elasticity to force the spindle 40 and its seat up to the fullest extent required.

a are a series of annular grooves cut in the spindle B, and designed to receive the end of the bolt E, more clearly shown in Fig. 2. This bolt is provided with a spindle, F, around 45 which the spiral spring G is placed. This spiral spring acts on one end against the collar f, formed on the spindle F. The other end of the spring rests against the back of the

bracket G', which is designed, as illustrated in Fig. 2, to receive the bolt E.

H is a pivoted pawl fitted behind the collar f, and attached to the handle I. When this handle is pressed down, the bolt E will naturally be drawn back, and if it is fitting into one of the annular grooves a this action withdraws it and permits the spindle B to move freely longitudinally within its chamber. As soon as the handle I is pressed down so as to withdraw the bolt E from the groove a, into which chamber it may at the time be fitting, 60 the power of the spring D causes the spindle to ascend, raising the same until the bolt E is permitted, by the release of the handle I, to spring into one of the annular grooves, when the spindle B will be securely held from moving longitudinally, and at the same time the seat A may be revolved freely. The top of the stand C is provided with a flanged sleeve, J, which fits into the chamber in which the spindle B is inserted. This sleeve J has a 65 notch cut in it to receive the end of the bracket G when inserted in position, which prevents the said sleeve revolving with the spindle.

With the view of operating the device by 75 foot I provide a foot-treadle, K, which I connect by the rod L to the lever I, so that by pressing on this foot-lever K the same effect will be produced as though the lever I were operated by hand.

I am aware of the Patents Nos. 123,172 and 208,000, and make no claim to the construction shown therein as forming part of my invention.

I attach importance to my flanged sleeve J, 85 the use of which prevents wearing of the stand and thus avoids "wabbling" of the spindle and seat, and also insures a closer contact between the bolt E and the groove in the spindle.

What I claim as my invention is—
1. In a revolving stool or chair, the combination, with the stand C, spindle B, having annular grooves a, and the flanged sleeve J, inserted in a socket in said stand, of the bracket G', secured in a recess in said stand, the

spring-actuated bolt E, carried by said bracket, the pivoted pawl H, and operating-lever I, working through a slot in said bracket, substantially as and for the purpose specified.

5 2. The combination, with the spindle B, stand C, spring D, and spring-actuated bolt E, of the pawl H, operating-lever I, the foot-

treadle K, and the rod L, substantially as and for the purposes specified.

Toronto, November 24, 1884.

W. A. C. MATTHIE.

In presence of—

C. C. BALDWIN,

JAS. E. MAYBEE.
